UNITED STATES PATENT OFFICE.

HAROLD E. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

NEEDLE-PICKER FOR CIRCULAR-KNITTING MACHINES.

1,078,676.

Specification of Letters Patent. Patented Nov. 18, 1913.

Application filed June 17, 1912. Serial No. 704,027.

To all whom it may concern:

Be it known that I, HAROLD E. HOUSEMAN, a citizen of the United States, residing at Philadelphia, county of Philadelphia, and 5 State of Pennsylvania, have invented a new and useful Improvement in Needle-Pickers for Circular-Knitting Machines, of which the following is a full, clear, and exact description, reference being had to the accompanying drawings, which form a part of this specification.

My invention relates to circular knitting machines, and particularly to mechanism for lifting out of action and depressing into 15 action certain needles, one at each oscillation of the machine, as in the operation of narrowing and widening during the knitting of the heel and toe of a stocking. Such machines comprise a needle cylinder and a 20 cam cylinder, one of which is alternately continuously rotated and oscillated, while the other is stationary, the cam cylinder carrying cams which act upon the needles to effect the knitting operation. In such machines it is old to provide mechanism, 25 mounted in a fixed position relative to the regular knitting cams, which, during oscillation, act to lift the needles out of action, one at a time and then to depress the needles into action one at a time.

The object of my invention is to provide mechanism of a simple character, not apt to get out of order, and adapted to act with certainty, and which will act to lift or 35 depress all the needles to a definite and uniform level.

In the drawings: Figure 1 is a side elevation of the needle cylinder and one of the pickers for lifting the needles. Fig. 2 is a 40 partial plan view of Fig. 1. Fig. 3 is a partial section through the needle cylinder and an end view of the picker.

The needles *a* are represented as mounted in a cylinder *b* and are actuated by the regular knitting cams (not shown) fixed relatively to the base *c*, to which are secured the pickers, one only of which is shown. For the purpose of describing the operation of the invention, I will assume that the needle cylinder is the rotatable and oscillatory element and that the regular knitting cams and pickers are the stationary elements, although the regular knitting cams and pickers may be the movable elements and the

needle cylinder the stationary element without affecting the relative operation of the parts.

Secured to the base *c* is the support *d*, on which is mounted the angle frame *e*, the vertical part of which is provided with two 60 guiding slots. The upper slot *f* extends in or near a horizontal direction. The lower slot *g* is located under the rear part of the slot *f* and is inclined downward and rearward at an angle (say) of about forty-five 65 degrees. A movable picker cam *h* has secured to it two pins *f'* and *g'* which extend respectively through the slots *f* and *g*. The plate *e* and the body of the picker-cam *h* are located a sufficient distance from the needle 70 bed to clear the laterally-projecting butts of the needles; but the upper or forward end of the picker-cam has a laterally extending head forming a cam-surface *i* and a projection *j*. A spring *k* connects the cam cylinder and the picker-cam and normally holds the latter in its forward position, in which the projection *j* extends substantially horizontally and the cam-surface *i* extends substantially vertically and in line of travel of 75 the butts of the needles.

In the oscillation of the needle cylinder, the butt of the particular needle which at any given oscillation is in advance strikes the cam surface *i* of the picker-cam *h* and 80 pushes the picker-cam in the direction of movement of the needle. Hence the pin *f'* will slide in the slot *f* and the pin *g'* in the slot *g* until the pins move to the rear ends of the slots. This pin and slot connection 85 imparts a definite and certain movement to the picker-cam and causes the needle engaging end of the cam to move upward in a direction more nearly horizontal than vertical. After the picker-cam has been moved 90 by the needle to its extreme position, the cam-face *i* extends at an angle not over forty-five degrees to the horizontal, affording an easy slope for the needle to travel upward. After the needle reaches the end of the cam-surface *i*, it has been lifted out of action 95 and to a definite level.

Owing to the fact that the body of the picker-cam *h* entirely clears the butts of the needles, the picker-cam, as it is elevated by 100 the first needle of the series, affords no obstruction to the travel of the second and subsequent needles at the lower level, the

butts of the other needles passing under the overhanging laterally-projecting head of the picker-cam. As soon as the needle has been lifted, the spring *k* draws the 5 picker-cam back toward its initial position, which it reaches after the remaining needle-butts of the lower tier of needles have passed from under the overhanging head of the picker-cam.

10 It will be observed that the movable part of the picker mechanism comprises only a single member—namely, the cam *h* thereby avoiding the complications of structure and the uncertainties of operating attending 15 picker mechanism composed of a plurality of mutually dependent movable parts.

It will be understood that when it is desired to lift alternately needles at opposite ends of a semi-circular bank of needles—as 20 in fashioning the heel and toe of a stocking—a duplicate picker will be provided on the opposite sides of the regular knitting cam. It will also be understood that pickers of the same construction—but reversed in 25 position—may be used to drop or depress the needles one or more at a time. When, therefore, I use such terms as “upward” or “downward” in the foregoing description, it is to be understood that the terms are 30 applicable only when the picker is used as lifter; and such terms in the claims are used only in a relative sense and as the equivalent of the opposite directions, when the device is used as a needle-dropper. It 35 will also be understood that suitable mechanism should be provided to render the pickers operative and inoperative at proper times, this mechanism not being herein shown because it forms no part of my invention. 40

Having now fully described my invention, what I claim and desire to protect by Letters Patent is—

1. An automatic picker for knitting machines comprising a unitary movable piece having at one end a cam face normally located in the path of travel of the needles to be elevated and extending at substantially a right angle to said path of travel, 45 two pins on the movable piece located at different distances from its cam face, and a frame having two slots respectively engaging the two pins and adapted to cooperate therewith to swing the movable 50 pieces toward a vertical position while simultaneously changing the angle of the cam to permit the needle to readily disengage therefrom.

2. An automatic picker for knitting machines comprising a unitary movable piece having a cam face located in the path of travel of the needles to be elevated, and adapted to be engaged and operated thereby, a frame, two guiding elements on the 60 movable piece, and two guiding elements on the

frame respectively engaging the two guiding elements on the movable piece and co-operating to permit the cam face to be turned toward the horizontal and moved a given distance in the direction of rotation 70 of the needles and a relatively shorter distance vertically, thereby allowing the level of the engaging needle to be lifted at an easy angle.

3. An automatic picker for knitting machines comprising a unitary movable piece having a needle engaging face normally located in the path of travel of the needles and at such an angle thereto as to be moved by the needle in advance, a frame, two guiding elements on the movable piece located at different distances from its needle engaging face and two guiding elements on the frame respectively co-operating therewith and adapted in said movement of the 80 movable piece, to cause the movable piece to turn during its bodily movement by the engaging needle, whereby the engaging face of the movable piece is moved toward the horizontal at the same time that it is moved 85 upward on a relatively slight incline.

4. An automatic picker for knitting machines comprising a cam having a cam face adapted to engage the first of a series of needles and adapted to be moved thereby in 90 the direction of movement of the needles, a frame having a plurality of guiding slots, and pins on the cam engaging the slots respectively and co-operating therewith to turn the cam to change the angle of the cam 95 face and permit the easy disengagement of the needles.

5. An automatic picker for knitting machines comprising a cam having a cam face adapted to engage the first of a series of 100 needles and adapted to be moved thereby in the direction of movement of the needles, a frame having a plurality of guiding slots, and pins on the cam engaging said slots, one of the slots being located relatively near 105 the cam face and extending in an approximately horizontal direction, and the other of the slots being located at a greater distance from the cam face and extending downwardly and rearwardly, whereby the 110 combined action of the slots will move the lower part of the cam downwardly and the upper end upwardly as the cam moves with the needle, thus causing the cam face to move upwardly in a direction at a relatively small angle to the horizontal.

6. An automatic picker for knitting machines comprising a cam having a cam face in line of travel of the needles and a projection below the line of travel of the needles, 115 whereby the first of a series of needles engaging said cam face will move the cam in the direction of movement of the needles, and a plurality of guides engaging the cam and adapted, as the cam is thus moved by 120 125 130

said needle, to coöperate to swing the lower part of the cam upward and thus elevate the cam face very gradually and at the same time swing it toward a horizontal position to allow the needle to ride up the same at an easy angle.

7. An automatic picker for knitting machines comprising an upright frame, a cam between the frame and the needles having a body adapted to clear the butts of the needles and an overhanging head having a cam face adapted to engage the first of a series of needles and to be moved thereby in the direction of movement of the needles, and a plurality of guides on the frame adapted to support the cam and coöperate to guide the cam face upward and at the same time swing it toward a horizontal position as the cam is moved by the engaging needle.

10 8. An automatic picker for knitting machines comprising a cam having a cam face adapted to engage the first of a series of needles and adapted to be moved thereby in the direction of movement of the needles, pins on the cam located at different distances from the cam-face, a cam-supporting frame, said frame having a relatively long and substantially horizontally-extending slot with which the nearer pin engages, and a relatively short slot, located beneath the rear part of the first slot and extending downwardly and rearward, with which the farther pin engages.

15 9. An automatic picker for knitting machines comprising a cam having a cam face adapted to engage the first of a series of needles and adapted to be moved thereby in the direction of movement of the needles, pins on the cam located at different distances from the cam-face, a cam-supporting frame, said frame having a relatively long and substantially horizontally-extending slot with which the nearer pin engages, and a relatively short slot, located beneath the rear part of the first slot and extending downwardly and rearward, with which the farther pin engages.

20 10. An automatic picker for knitting machines comprising a cam having a cam face adapted to engage the first of a series of needles and adapted to be moved thereby in the direction of movement of the needles, pins on the cam located at different distances from the cam-face, a cam-supporting frame, said frame having a relatively long and substantially horizontally-extending slot with which the nearer pin engages, and a relatively short slot, located beneath the rear part of the first slot and extending downwardly and rearward, with which the farther pin engages.

25 11. An automatic picker for knitting machines comprising a cam having a cam face adapted to engage the first of a series of needles and adapted to be moved thereby in the direction of movement of the needles, pins on the cam located at different distances from the cam-face, a cam-supporting frame, said frame having a relatively long and substantially horizontally-extending slot with which the nearer pin engages, and a relatively short slot, located beneath the rear part of the first slot and extending downwardly and rearward, with which the farther pin engages.

30 12. An automatic picker for knitting machines comprising a cam having a cam face adapted to engage the first of a series of needles and adapted to be moved thereby in the direction of movement of the needles, pins on the cam located at different distances from the cam-face, a cam-supporting frame, said frame having a relatively long and substantially horizontally-extending slot with which the nearer pin engages, and a relatively short slot, located beneath the rear part of the first slot and extending downwardly and rearward, with which the farther pin engages.

35 9. An automatic picker for knitting machines comprising a unitary movable piece having a cam face normally located in the path of travel of the needles to be elevated and extending at substantially a right angle to said path of travel, two pins on the movable piece located at different distances from its cam face, and a frame having two slots engaging the two pins and co-operating to

permit the piece as a whole to move with the needle while constraining the cam end of the movable piece to move upwardly and the opposite end of the movable piece downwardly, thereby guiding the cam face to a higher level in the direction at a relatively small angle to the horizontal while changing the angle of the cam face to permit the needle to readily disengage therefrom at the end of the movement of the movable piece. 45 50

10. An automatic picker for knitting machines comprising a unitary movable piece having at one end a cam face normally located in the path of travel of the needles to be elevated and extending at substantially a right angle to said path of travel, two pins on the movable piece located at different distances from its cam face, and a frame having two slots, the longer one of which engages the pin nearest the cam face and extends in a substantially horizontal direction while the shorter of which engages the pin farthest from the cam face and extends obliquely downward, whereby when the movable piece is moved forward by the needle engaging it the same will swing on its axis toward a vertical position and simultaneously elevate its cam end and depress its opposite end, thereby lifting the cam face in a direction at a relatively small angle to the horizontal while changing the angle of the cam to permit the needle to readily disengage therefrom at the end of the movement of the movable piece.

In testimony of which invention, I have hereunto set my hand, at Philadelphia, on this 13th day of June, 1912.

HAROLD E. HOUSEMAN.
